UNITED STATES PATENT OFFICE.

NIELS CHRISTIAN SORENSEN, OF CHICAGO, ILLINOIS.

TONGS.

1,220,899.

Specification of Letters Patent. Patented Mar. 27, 1917.

Application filed May 10, 1916. Serial No. 96,472.

To all whom it may concern:

Be it known that I, NIELS C. SORENSEN, a subject of the King of Denmark, and a resident of the city of Chicago, county of Cook, 5 and State of Illinois, have invented certain new and useful Improvements in Tongs, of which the following is a specification.

My invention relates to improvements in tongs especially designed for use by blacksmiths, or the like, in holding small pieces 10 of metal in welding or otherwise treating the same.

The object of my invention is the production of a device of this character which will 15 be of durable and economical construction, one which will be adapted to securely hold the object engaged thereby, and one which may be readily and easily operated.

Other objects will appear hereinafter. 20 With these objects in view, the invention consists in the combinations and arrangements of parts hereinafter described and claimed.

The invention will be best understood by 25 reference to the accompanying drawings forming a part of this specification, and in which,

Figure 1 is a perspective view of a pair 30 of tongs embodying the invention, Fig. 2 is a substantially central longitudinal section of the tongs, and

Fig. 3 is a section taken on line $x-x$ of Fig. 2.

The preferred form of construction, as 35 illustrated in the drawings, comprises a tubular handle 1 bifurcated at its front end to form spaced parallel branches 2. Arranged between the branches 2 are gripping jaws 3 pivotally connected intermediate their 40 ends with the branches 2 by means of a pivot pin 4 which passes through flanges or webs 5 provided at the inner sides of jaws 3.

Shiftably mounted in the handle 1 is a rod 6 bifurcated at its front end and operatively 45 connected by means of a toggle 7 with the rearward ends of jaws 3. Said toggle, as will be seen, is pivotally connected at its ends with the rearward ends of flanges or webs 5, pivot pin 8, at the knee joint of said 50 toggle, having its ends extended for sliding engagement with elongated longitudinally extending slots 9 which are formed in the handle branches 2, as clearly shown in Fig. 3. The outer ends of the links of toggle 7 55 are formed with square shoulders 10 which are adapted to engage against the inner sides

of jaws 3 to limit rearward rocking of the inner ends of said toggles. The slots 9 are so arranged that the same serve to limit rearward movement of the pin 8, and thus 60 coöperate with the corners 10, in the performance of the function above referred to.

Encircling the rearward end of rod 6 is a helical compression spring 11 which is interposed between the rearward end of handle 1 and an enlargement 12 provided at the rearward extremity of said rod. The arrangement is such, as will be seen, that said spring will serve to normally hold the jaws 3 in gripping relation, said jaws being 70 rocked to releasing position through the medium of an angular hand lever 13 which is fulcrumed at 14 to the bifurcated rearward end of handle 1, said lever being pivotally connected at 15 with the rearward end of 75 rod 6. The free end of said hand lever projects forwardly as seen, for ready manual engagement in the gripping of the rearward end of handle 1, so that, when it is desired to rock the jaws 3 to releasing position, it is only necessary to depress said lever. During use of the tool, the jaws are held in gripping relation through the pressure of spring 11, the pressure of the hand 80 of the operator being used only to rock the 85 gripping jaws to releasing position.

The spring 11 is located at the extreme rearward end of the tool so that the same will not become heated and thus the temper removed therefrom, when the front end of 90 the tongs is engaged with a hot piece of work, or is thrust into the fire, during use of the tool. The slots 9 serve to guide the pin 8, of the knee joint of the toggle, in the shifting of the rod 6 and thus relieve said 95 rod of lateral strains which the same would otherwise be required to bear.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and 100 modifications as come within the scope of the appended claims.

Having described my invention what I claim as new and desire to secure by Letters Patent is:

1. In a device of the class described, the combination of an elongated handle having

a bifurcated front end; a pair of gripping jaws arranged between the branches at the front end of said handle and pivotally connected intermediate their ends with said 5 branches; means for operating said jaws, said means comprising a rod movable longitudinally of said handle; a toggle having its ends connected with the rearward ends of said jaws; a pin connecting the knee joint 10 of said toggle with the forward end of said rod whereby said jaws will be operated upon shifting of said rod; means co-operating with said pin for guiding the same in a direction longitudinally of said handle upon shifting 15 of said rod; and means for shifting said rod, substantially as described.

2. In a device of the class described, the combination of an elongated handle having a bifurcated front end; a pair of gripping 20 jaws arranged between the branches at the front end of said handle and pivotally connected intermediate their ends with said branches; means for operating said jaws, said means comprising a rod movable longitudinally of said handle; a toggle having its ends connected with the rearward ends of said jaws; a pin connecting the knee joint 25 of said toggle with the forward end of said rod whereby said jaws will be operated upon shifting of said rod, said handle branches having longitudinally extending slots engaging 30 with the ends of said pin for guiding

the same in a direction longitudinally of said handle upon shifting of said rod; and means for shifting said rod, substantially as 35 described.

3. In a device of the class described, the combination of an elongated tubular handle; a pair of gripping jaws having pivotal connection intermediate their ends with the front ends of said handle; means for operating said jaws, said means comprising a rod mounted in said handle for longitudinal shifting; a toggle operatively connecting the front end of said rod with the rearward ends 40 of said jaws, whereby said jaws will be operated upon shifting of said rod; a helical compression spring encircling the rearward end of said rod and interposed between the rearward end of said handle and an enlargement 45 on said rod for normally holding said jaws in gripping relation; and a hand lever fulcrumed on the rearward end of said handle and operatively connected with the rearward end of said rod for shifting the latter. 50 substantially as described.

In testimony whereof I have signed my name to this specification in the presence of two subscribing witnesses.

NIELS CHRISTIAN SORENSEN.
